CONSTANT TEMPERATURE BATH

Alan L. Litman, 114 Hartwood Drive, Pittsburgh, Pa.

Filed Mar. 4, 1963, Ser. No. 73,805

Term of patent 3½ years

(Cl. D16—2)

The figure is a perspective view of a constant temperature bath showing my new design.

The undisclosed side is substantially the same as the side shown and the rear is unornamented.

I claim:

The ornamental design for a constant temperature bath, substantially as shown and described.
